Filed Nov. 29, 1972, Ser. No. 310,639

Term of patent 7 years

Int. Cl. D6—01

U.S. Cl. D6—37

FIG. 1 is a perspective view looking toward the front of a combined chair and leg support embodying my new design;

FIG. 2 is a perspective view looking toward the rear thereof;

FIG. 3 is a top plan view thereof;

FIG. 4 is a bottom plan view thereof; and

FIG. 5 is an enlarged fragmentary side view showing the position of a front portion of the seat thereof as it sometimes appears when a combined chair and leg support is in use.

I claim:

The ornamental design for a combined chair and leg support, as shown.
